CONTAINER BLANK TO FORM INTO
VARIOUS CONTAINERS

Dexter T. Bowden, Marblehead, Mass.

Application September 2, 1950, Serial No. 182,944

3 Claims. (Cl. 206—44.12)

1

This invention relates to a container blank.

One object of my invention is to provide a container blank that, when in various assembled positions, provides either a closed shipping container, an open display container for a store counter, or a dispensing container that may be hung on a pin or nail projecting from a wall or the like.

Another object is to provide such a container blank having a relatively small number of portions that can easily be assembled to form the three forms of containers mentioned above, and without having any of said portions appearing to be superfluous in any of the various forms of containers.

The foregoing and other objects which will appear as the nature of the invention is better understood, may be accomplished by a construction, combination and arrangement of parts such as is disclosed by the drawings. The nature of the invention is such as to render it susceptible to various changes and modifications, and therefore, I am not to be limited to the construction disclosed by the drawings nor to the particular parts described in the specification; but am entitled to all such changes therefrom as fall within the scope of my claims.

In the drawings:

Figure 1 is a top plan view of my container blank lying flat and ready to be formed into any one of the three containers above referred to.

Figure 2 is a perspective view showing my container blank early in the process of forming a dispensing container and Figure 3 is a perspective view showing said blank later in said process.

Figure 4 is a perspective view of said dispensing container in completed form ready to hang on a wall, looking at the front thereof. Figure 5 is a similar perspective view but looking at the rear thereof.

Figure 6 is a longitudinal, sectional view of said dispensing container shown in position attached to a wall.

Figure 7 is a perspective view showing said dispensing container in the process of being changed to a display container.

Figure 8 is a perspective view of said display container in completed form, looking at the front thereof, as used on a counter to display merchandise. Figure 9 is a similar perspective view; but looking at the rear thereof.

2

Figure 10 is a perspective view showing said display container early in the process of being changed to a closed shipping container and Figure 11 is a similar view showing it later in the process. Figure 12 is a similar view showing the final step in the process of closing said shipping container.

Figure 13 is a perspective view of said shipping container completed and closed looking at the front thereof. Figure 14 is a similar perspective view; but looking at the rear thereof.

As illustrated, my display container may be made from a single piece of material, such as flat cardboard, as shown in Figure 1 of the drawings. It has a back 16 in the lower half portion of which 15 two slits 18 are made and at the middle portion a left tab 20 and a right tab 21 are struck out of said back 16 and may extend slightly into the interior of said container. In the upper portion 20 a hole 22 is provided whereby the container may be hung on a pin or nail 23 projecting from the wall W, when it is serving as a dispenser, as shown in said Figure 6.

Said container has a top 24 commencing at a score 26 between it and said back 16. It also has a bottom 28 having a delivery opening 30 therein which is a clear cutout extending from the front edge of said bottom 28 to the rear half portion. Said bottom commences at a score 32 between it and said back 16.

At the left of said top 24 is a left upper brace 34 commencing at a score 35 between it and said top 24, while at the right thereof is a right upper brace 37 commencing at a score 38 between it and said top. At the left of said bottom 28 is a left lower brace 40 commencing at a score 41 while at the right thereof is a right lower brace 42 commencing at a score 43 between it and said bottom 28. In assembling the portions of my container said left braces 34 and 40 overlap as shown, for instance, in Figure 2 of the drawings, as do the two said right braces 37 and 42.

There is a left outer side portion 45 commencing at a score 46 and a right outer side portion 48 commencing at a score 49, said scores 46 and 49 being made between said side portions and said back 16, and said side portions are not directly connected to said braces 34, 40, 37 and 42.

There is an inner left side portion 51 extending from a score 52 between it and said left outer side portion 45 and at an intermediate port of 50 said score 52 is a locking slit 53 between said

inner and outer left side portions 51 and 45 respectively. This intermediate slit 53 provides an upper catch portion 54 at the upper part of said score 52 and a lower catch portion 55 at the lower part of said score 52 just above and below respectively the termination of said locking slit 53. There is a lip 56 extending from a score 57 between it and said inner left side portion 51 which extends under said tab 20 when my container is assembled as illustrated at the left in said Figure 2.

There is an inner right side portion 58 extending from a score 59 between it and said right outer side portion 48 and at an intermediate part of said score 59 is a right locking slit 60 between said inner and outer right sides 58 and 48 respectively. This intermediate slit 60 provides an upper catch portion 61 at the upper part of said score 59 and a lower catch portion 62 at the lower part of said score 59 just below the termination of said right locking slit 60. There is a lip 63 extending from a score 64 between it and said inner right side 58. These two pairs of inner and outer side portions, and said braces between the latter, provide the two main sides of my container.

The foregoing provides an open container with a back, top, bottom and sides. It is also provided with a master front 65 embodying a front closure portion 66 which provides the entire front for the shipping container shown in said Figure 13. Said front closure portion has an arcuate slit 68 in the upper half portion to thereby define a curved display head 66a in said front closure portion 66. Above said arcuate slit 68 is a supporting portion 66b forming part of said front closure portion 66; but when the container is used as a dispenser or as a display, as shown in Figures 4 and 8 of the drawings respectively, said supporting portion 66b serves as a back support for part of said front display head 66a. A score 72 between said top 24 and said supporting portion 66b divides said front closure portion 66 from said top 24.

There is a left display wing 74 at the left side of said front closure portion 66 with a score 75 between them, the top of said wing 74 commencing where said arcuate slit 68 terminates at the left. There is also a right display wing 77 at the right side of said front closure portion 66 with a score 78 between them, and its top likewise commences where said arcuate slit 68 terminates at the right. These display wings 74 and 77 constitute inner side portions of the container when it is in closed or shipping position.

There is a display wing left support 80 with a score 81 between it and said supporting portion 66b, and another score 82 between it and said left display wing 74. This left support 80 is directly rearward of said left display wing 74 when my container is used either as a dispenser or as a display. Also there is a display wing right support 84 with a score 85 between it and said supporting portion 66b and another score 86 between it and said right display wing 77. This right support 84 is directly rearward of said right display wing 77 when my container is used as a dispenser or as a display. These display wings increase the display advertising space.

Said master front 65 has a portion serving as a bottom outside cover portion 88 divided from the lower end of said front closure portion 66 by a score 89, and beyond said bottom cover 88 is a retainer 91 divided from it by a score 92, and extending from said retainer 91 are two locking

tabs 93 that are adapted to extend into said slits 18 in said back 16 when the container is closed, as for shipment. These portions 88, 91 and 93, together with said front portion 66, except said supporting portion 66b, serve as a front when my container is formed as a dispenser, being open at the lower end below said tabs 93, as shown in said Figure 4, to permit withdrawal of merchandise.

A left side upper locking member 96 extends laterally from the lower left side of said front closure portion 66, being divided therefrom by a score 97 which score terminates at its upper extremity in a slit 98 to thus provide a short, upper locking portion 96a in said side locking member 96 which extends through said locking slit 53 and under said upper catch portion 54 when a container is formed to use as a dispenser as shown in Figures 1-6 inclusive of the drawings. This locking member 96 has an arcuate outside edge 100, as shown, to facilitate smooth rotative movement when inserting it into said locking slit 53.

There is a right side upper locking member 101 which extends laterally from the lower right side of said front closure portion 66, being divided therefrom by a score 102 which terminates at its upper extremity in a slit 103 to thus provide a short upper locking portion 101a in said locking member 101 which extends through said locking slit 60 and under said upper catch portion 61 when my container is formed to use as a retainer. This locking member 101 has an arcuate outside edge 105 as shown.

A left side lower locking member 106 extends laterally from the left of said bottom outside cover 88, being divided therefrom by a score 107 which terminates at its lower extremity in a slit 108 to thus provide a short, lower locking portion 106a in said locking member 106 which extends through said locking slit 53 and under said lower catch portion 55 when my container is formed to use as a dispenser. This locking member 106 has an arcuate outside edge 110 as shown and when said left side locking members 96 and 106 are inserted into said locking slit 53 they overlap somewhat as indicated in said Figure 3.

There is a right side lower locking member 111 which extends laterally from the right of said bottom outside cover 88, being divided therefrom by a score 112 which terminates at its lower extremity in a slit 113 to thus provide a short, lower locking portion 111a in said locking member 111 which extends through said locking slit 60 and under said lower catch portion 62 when my container is formed to use as a dispenser. An arcuate outside edge 115 partly bounds said locking member 111. Said right side upper locking member 101 and the lower one 111 provide a half circle when my container is laid flat as shown in said Figure 1, and this is also true of the left side locking members 96 and 106.

To assemble my container from the single sheet shown in said Figure 1, said pairs of braces 34 and 40, and 37 and 42, are brought into line respectively with said left score 43 and said right score 49, overlapping each other as indicated at the right in said Figure 2. Then the two outer side portions 45 and 48 are moved over said braces to a position where they also extend straight forward. The two inner sides 51 and 58 are moved to the inside in a similar position, with said lips 56 and 63 parallel with said back 16. The tabs 20 and 21 are placed over said lips 56 and 63 respectively, which retains them in position against said back 16, thus holding the sides

75

of my container in predetermined position with said bottom 28 and top 24 extending forwardly also, and with said slits 53 and 60 at the upper point between the inner and outer side portions in each instance. As thus formed at this point an open container is provided which remains the same for all three forms it may later take.

To form a dispenser, starting with said open container, said left and right display wings 74 and 77 are folded against said left and right supports 80 and 84 and said display head portion 66a of said front closure portion 66 is thereby moved to the position shown in said Figures 3 and 4, which is above and slightly forward of said top 24 with said supporting portion 66b rearwardly thereof. Then the pair of said locking members 96 and 106, and the other pair 101 and 111 are overlapped somewhat, as shown in said Figure 3, and inserted in said slits 53 and 60 respectively, rotating them downwardly somewhat to positions where the left locking portions 96a and 106a are under said catch portions 54 and 55 respectively. Likewise said right locking portions 101a and 111a are under said catch portions 61 and 62 respectively. In this position said master front 65 except for said supporting portion 66b, is wholly at the front, with a space between said bottom 28 and said locking tabs 93 for the fingers to reach into the container and withdraw merchandise. This dispenser may be placed, at said hole 22, on a nail or screw head projecting from a wall, as illustrated in said Figure 6, thus serving as a dispenser and also providing a large overhead display for advertising.

To change said dispenser into a counter display container the fingers are inserted into the container under said front closure portion 66 and the latter is pushed outwardly thus moving said locking portions out of said slits, whereupon the said open container is ready to take form as a counter display container. This is done by pushing said locking members 96, 106, 101 and 111 inside the container parallel with said side portions 51 and 58, or members 96 and 101 may be placed against said top 24 and members 106 and 111 may be placed flat against said back 16, and also said bottom outside cover portion 88 and said retainer 91 and its tabs 93 are pushed flat against said back 16, while the lower part of said front closure portion 66 is made flush against said top 24. This leaves said display head 66a and said display wings 74 and 77 in prominent view above the open container as shown in said Figure 8, with said back 16 serving as a bottom.

To provide a closed, shipping container, starting with the said open container, said display wings 74 and 77 and their two supports 80 and 84, as well as said upper locking members 96 and 101, are inserted into said container in a position parallel with the sides thereof, this reinforcing said sides. Said lower locking members 106 and 111 are inserted between said pairs of side portions 45, 51 and 48, 58 respectively, or they may be folded to a position parallel with said bottom cover portion 88 and the latter is drawn to a position outside of and next to said bottom 28, and then said retainer 91 is drawn outside of and over the lower part of said back 16 and the locking tabs 93 are inserted into said slits 18. This provides a closed, shipping container in which the whole of said front closure portion 66, including said supporting portion 66b, constitutes the front of the closed container.

What I claim is:

1. A container blank scored to form a back, top, bottom and two sides, each said side embodying an inner side portion and an outer side portion inwardly hinged along a scored line and having

top, bottom and two sides, said back having a slit therein adjacent the bottom, each said side embodying an inner side portion and an outer side portion inwardly hinged along a scored line and having a slit that extends longitudinally between them along said scored line, a master front 5 hinged to said top along a scored line, said master front embodying a front closure portion and a supporting portion in scored relationship to said 10 top, said front closure portion having an arcuate slit therein dividing it from said supporting portion and defining a display head portion adapted to extend above said top, said master front also embodying a bottom cover portion hinged to 15 said front closure portion along a scored line and a retainer in scored relationship to said bottom cover portion, said retainer having a tab at one extremity adapted to enter said slit in said back when said blank is in the form of a shipping container, similar pairs of locking members extending laterally from the side of the bottom cover portion and the adjacent end of the front closure portion and hinged thereto along scored lines, each pair defining a substantially semi-circular area and separated from each other by a cut extending from and aligned with the scored line separating said bottom cover portion from said front closure portion, said pairs of locking members being adapted to enter said second-named slits when said master front is spaced 20 from said bottom and is folded in the position to form a dispenser.

2. A container blank scored to form a back, top, bottom and two sides, said back having a 25 slit therein adjacent the bottom, each said side embodying an inner side portion and an outer side portion inwardly hinged along a scored line and having a slit that extends longitudinally between them along said scored line, a master front hinged to said top along a scored line, said master front embodying a front closure portion and a supporting portion in scored relationship to said 30 top, said front closure portion having an arcuate slit therein dividing it from said supporting portion and defining a display head portion adapted to extend above said top, said master front also embodying a bottom cover portion hinged to 35 said front closure portion along a scored line and a retainer in scored relationship to said bottom cover portion, said retainer having a tab at one extremity adapted to enter said slit in said back when said blank is in the form of a shipping container, similar pairs of locking members extending laterally from the side of the bottom cover portion and the adjacent end of the front closure portion and hinged thereto along scored 40 lines, each pair defining a substantially semi-circular area and separated from each other by a cut extending from and aligned with the scored line separating said bottom cover portion from said closure portion, said pairs of locking members being adapted to enter said second-named slits when said master front is spaced from said bottom and is folded in the position to form a dispenser, said locking members each having a slit 45 extending from the outside of and part way along said scored lines that extend between a said locking member and said bottom cover portion and between a said locking member and said front closure portion.

3. A container blank scored to form a back, top, bottom and two sides, each said side embodying an inner side portion and an outer side portion inwardly hinged along a scored line and having

75 a slit that extends longitudinally between them

along said scored line, a master front hinged to said top along a scored line, said master front embodying a front closure portion and a supporting portion in scored relationship to said top, said front closure portion having an arcuate slit therein dividing it from said supporting portion and defining a display head portion adapted to extend above said top, said master front also embodying a bottom cover portion hinged to said front closure portion along a scored line and a 10 retainer in scored relationship to said bottom cover portion, similar pairs of locking members extending laterally from the side of the bottom cover portion and the adjacent end of the front closure portion and hinged thereto along scored 15 lines, each pair defining a substantially semi-circular area and separated from each other by a cut extending from and aligned with the scored line separating said bottom cover portion from said front closure portion, said pairs of locking 20 members being adapted to enter said second-named slits when said master front is spaced from said bottom and is folded in the position to form a dispenser.
